JARRING TOOL

Charles O. Denning, Houston, Tex., assignor to
A-1 Bit & Tool Company, Inc., Houston, Tex.,
a corporation of Texas

Application December 27, 1947, Serial No. 794,153

7 Claims. (Cl. 255—27)

1

This invention relates to a jarring tool.

An object of the invention is to provide a tool which is shaped to be lowered into a well bore and is engageable with an object stuck in the bore and whereby vibrations may be successively imparted to the stuck object and the object thus jarred loose and removed from the bore.

It is another object of the invention to provide a jarring tool of the character described which is of such construction that well fluid may be forced through it so as to maintain the necessary circulation.

It is a further object of the invention to provide a tool of the character described which may be easily reset after a stroke to the end that as many successive strokes as desired may be delivered until the stuck object is jarred loose.

One form of the tool is specially designed for operation by a wire line while another form has been designed to be operated by a drill stem as will be more specifically hereinafter explained.

Other objects and advantages will be apparent from the following specification which is illustrated by the accompanying drawings, wherein—

Figure 1 is a vertical, sectional view of the upper end of the tool in engaged position preparatory to taking a stroke.

Figure 2 is a vertical, sectional view of the lower end thereof.

Figure 3 is an enlarged, cross-sectional view taken on the line 3—3 of Figure 1.

Figure 4 is an enlarged cross-sectional view taken on the line 4—4 of Figure 2.

Figure 5 is a vertical, sectional view of the upper end of the tool with the parts in initial upstroke position.

Figure 6 is a vertical, sectional view of the lower end thereof.

Figure 7 is a side elevation partly in section of the complete tool in engagement with the stuck object.

Figure 8 is a vertical, sectional view of the upper end of the tool designed to be operated by a drill stem.

Figure 9 is a vertical, sectional view of the lower end thereof and

Figure 10 is a side elevational view, partly in cross-section showing the grappling tool of the invention engaged with a stuck pipe.

Referring now more particularly to the form shown in Figures 1 to 7 inclusive, the numeral 1 designates the jar stem housing threaded into the upper end of which there is an impact head, or anvil, 2.

Screwed into the lower end of the housing there

2

is a coupling 3 whose lower end is reduced in diameter and downwardly and inwardly tapered forming a latch expander 4.

There is a tubular latch housing 5 whose upper end is screwed onto the lower end of the coupling 3. The lower end of this latch housing is reduced and externally threaded and screwed onto said reduced lower end and depending therefrom there is a tubular spring housing 6 whose lower end terminates in a reduced externally threaded pin 7.

Working axially through the jar stem housing 1 there is a jar stem 8 and on this stem, and preferably formed integrally therewith and located in the housing 1 there is the jar hammer 9. Beneath this hammer the stem 8 is reduced and extends on down axially through the coupling 3 and within said coupling the stem is provided with the guides 10 which are spaced apart around the stem, as shown in Figure 3, to provide circulating spaces 11.

The lower end of the jar stem terminates in an inverted conical shaped head 12.

Slidably axially through the reduced lower end of the latch housing 5 there is a latch stem 13 which extends down into the spring housing 6.

Screwed on the lower end of the stem 13 there is a nut 14 which is maintained against detachment by a lock nut 15 and surrounding the stem 13 and interposed between the nut 14 and the lower end of the latch housing there is a strong coil spring 16.

There is a latch designated generally by the numeral 17 in the latch housing and whose lower end is screwed onto the upper end of the latch stem 13. The upper end of the latch is vertically slotted thus providing a plurality of flexible latch arms 18. The upper ends of these arms are inwardly thickened forming the catches 19 whose upper ends are formed with the upwardly flared faces 20 which are normally spaced beneath the latch expander 4.

The housings 1, 5 and 6 are provided with radial openings, as 21, and circulation may be maintained through these openings and through the circulating spaces 11.

The tool may be lowered into the well by means of a flexible line whose lower end is connected to the socket 22 which, in turn, is attached to the upper end of the jar stem 8.

Any selected type of grappling tool, such as 23, may be attached to the pin 7, as shown in Figure 7. This grappling tool is of a design to readily engage over the head 24 which is carried by the upper end of the conventional side wall core bar-

rel, the tool herein described being particularly designed for engaging with and removing core barrels that may become stuck in the well bore; although any conventional type of grapple may be provided that will readily take hold of any object, such as pipe or the like, that may become stuck in the well bore.

When the tool is lowered into the well bore and engaged with the stuck object the latch 17 will hang on the head 12, as shown in Figures 1 and 7, with the upwardly flared faces of the latch arms spaced beneath the latch expander.

An upward pull may then be taken on the line causing a relative upward movement of the jar stem, the latch and the latch stem thus placing the spring 16 under compression.

As the latch moves upwardly its faces 20 will come into contact with the tapering face of the expander 4 and thus gradually expand the latch arms and eventually the catches 19 will be disengaged from the head 12 thus allowing an instantaneous upward movement of the jar stem 8 and the hammer 9 will strike the lower end of the anvil 2 with a sudden impact thus creating a sudden upward movement of the housings and the grapping tool 23 which will be imparted to the stuck object.

This operation may be repeated as often as necessary by merely lowering the jar stem until the head 12 is beneath and in engagement with the catches 19 of the latch arms whereupon another upward pull may be taken as before and the process repeated as often as necessary to jar loose the stuck object.

Referring now to the form of tool illustrated in Figures 8, 9 and 10, this type is designed to be attached to and operated by a conventional drill stem, as 25, to whose lower end the coupling 26 is attached and the jar stem 8a has its upper end connected to this coupling 26. This stem 8a is tubular throughout having the fluid channel 27 extending through it from end to end and leading from the channel through the drill stem. The jar stem 8a is provided with the jar hammer 9, as shown in the other figures, and incorporated in said stem there is the conical shaped head 12a corresponding in location and use to the head 12 but said stem 8a is extended beneath said head, as shown in Figure 9. It extends on down into the latch stem 13a which in Figures 8, 9 and 10 is of tubular formation and surrounding the lower end of the jar stem 8a there is a seal ring 28 which forms a seal between the jar stem and the latch stem 13a; also in this form of the tool the lower end or pin 7a of the spring housing 6a is of tubular formation and the latch stem 13a is extended down into it and sealed with the lower end of said spring housing by means of the annular seal 29.

In this embodiment of the tool there is shown a tapering tap 30 which is attached to the lower end of the spring housing 6a and which is adapted to be screwed into the stuck pipe 31 which is to be pulled. This tap has a fluid passageway 32 therethrough and fluid may be circulated downward through the tool and through the stuck pipe 31 and back up around said pipe to, in some cases, wash it loose to facilitate its removal.

In other respects the type of tool shown in Figures 8, 9 and 10 is similar to that shown in Figures 1 to 7, inclusive.

There has been shown and described what are now considered to be preferred forms of the invention by way of illustration only while the broad

principle of the invention will be defined by the appended claims.

What I claim is:

1. A jarring tool comprising, a housing structure, means for connecting said structure to a stuck object, an anvil carried by the housing structure and having an impact face, an axial stem slidable in said structure, means connecting the stem to a fishing string, a hammer on the stem opposing, and spaced from, said face, latch means in the housing structure in releasable engagement with the stem and having a tapering face, a yieldable member operatively disposed between the housing structure and stem and adapted to be placed under compression upon application of tension to the stem and an expander fixed with respect to the housing and positioned to engage said face to release the latch means from the stem, upon application of such tension, to allow the hammer to strike the anvil face, under the influence of such tension, to create a jar.

2. A jarring tool adapted to be lowered into a well and comprising, a housing structure, means for connecting said structure to an object stuck in a well, an impact face carried by the housing structure, an axial stem slidable in said structure, means connecting the stem to a fishing string, a hammer on the stem opposing, and spaced from, said face, opposing flared latch means in the housing structure in releasable engagement with the stem, a yieldable member operatively disposed between the latch means and housing structure and arranged to be placed under compression upon application of tension to the stem and an expander arranged to engage within the latch means for releasing the latch means from the stem, upon application of such tension to allow the hammer to strike said face, under the influence of such tension, to create a jar.

3. A jarring tool for wells comprising, a housing structure, means for connecting said structure to an object stuck in a well, an anvil carried by the housing structure and having an impact face, an axial stem slidable in said structure, means connecting the stem to a fishing string, a hammer on the stem opposing, and spaced from, said face, expandible latch means in the housing structure in releasable engagement with the stem and having tapering faces, a yieldable member operatively disposed between the housing structure and the latch means and arranged to be placed under compression by movement of the latch means, upon application of tension to the stem, and an expander fixed relative to the housing and forming means arranged to engage said faces for releasing the latch means from the stem, upon such movement of the latch means, to allow the hammer to strike the anvil face, under the influence of such tension, to create a jar.

4. A jarring tool for recovering a stuck object from a well and having one end thereof connectable to an operating string and the other end thereof to the stuck object, said tool comprising: an elongated housing; a stem mounted for longitudinal slidable movement therein and projecting from one end thereof; an anvil carried by said housing; a hammer carried by said stem in longitudinal spaced opposition to said anvil for contact therewith upon predetermined relative extensible movement between said housing and said stem; latch carrying means mounted for longitudinal slidable movement in said housing; at least one latch finger carried by said means and retainingly engageable with said stem in a relative contracted position of the latter with

respect to said housing; means carried by said housing for engaging and positively unlatching said latch finger to release said stem upon predetermined relative extensible movement between the latter and said housing less than said first mentioned relative movement; and resilient means engaged with said latch carrying means and said housing for opposing relative extensible movement between said housing and said stem when the latter is engaged by said latch finger.

5. The structure defined in claim 4 in which the resilient means comprises a compression coil spring.

6. The structure defined in claim 4 in which the stem has a shoulder thereon; the latch carrying means carries a plurality of annularly arranged spring latch fingers having outwardly tapering end portions and inwardly extending catches for engagement with said shoulder; and the unlatching means comprises a complementary tapered annular projection for engagement with the inner surfaces of said finger end portions to cam the latter radially outwardly.

7. A jarring tool for recovering a stuck object from a well and having one end thereof connectable to an operating string and the other end thereof to the stuck object, said tool comprising: an elongated housing having a fluid opening at one end thereof; a tubular stem mounted for longitudinal slideable movement in said housing and projecting from the other end thereof; an anvil carried by said housing; a hammer carried by said stem in longitudinal spaced opposition to said anvil for contact therewith upon predetermined relative extensible movement between said housing and said stem; tubular latch carrying means mounted for longitudinal slideable movement in said housing, the inner end of said stem being sealingly telescoped within one end of said

latch-carrying means and the other end of the latter being sealingly telescoped within said housing opening, whereby said housing, latch-carrying means and stem provide a passageway for conducting fluid longitudinally through the tool; at least one latch finger carried by said means and retainingly engageable with said stem in a relative contracted position of the latter with respect to said housing; means carried by said housing for engaging and positively unlatching said latch finger to release said stem upon predetermined relative extensible movement between the latter and said housing less than said first mentioned relative movement; and resilient means engaged with said latch carrying means and said housing for opposing relative extensible movement between said housing and said stem when the latter is engaged by said latch finger.
